US00D743460S

(12) **United States Design Patent**
Suzuki et al.

(10) **Patent No.:** **US D743,460 S**
(45) **Date of Patent:** ** *Nov. 17, 2015

(54) **IMPELLER BLADE FOR SHOTBLAST MACHINE**

(71) Applicant: **Sintokogio, Ltd.**, Nagoya-shi, Aichi (JP)

(72) Inventors: **Hiroaki Suzuki**, Toyokawa (JP); **Masato Umeoka**, Toyokawa (JP)

(73) Assignee: **Sintokogio Ltd.**, Nagoya-shi (JP)

(*) Notice: This patent is subject to a terminal disclaimer.

(**) Term: **14 Years**

(21) Appl. No.: **29/488,899**

(22) Filed: **Apr. 24, 2014**

(30) **Foreign Application Priority Data**

Oct. 31, 2013 (JP) 2013-025417

(51) **LOC (10) Cl.** **15-09**

(52) **U.S. Cl.**

USPC **D15/139**

(58) **Field of Classification Search**

USPC D7/383; D15/122, 123, 124, 131, 138, D15/139, 140; D23/379; D24/110

(57) **CLAIM**

The ornamental design for an impeller blade for shotblast machine, as shown and described.

DESCRIPTION

FIG. 1 is a front view of an impeller blade for shotblast machine showing our new design;

FIG. 2 is a rear view thereof;

FIG. 3 is a left side view thereof;

FIG. 4 is a right side view thereof;

FIG. 5 is a top plan view thereof;

FIG. 6 is a bottom plan view thereof;

FIG. 7 is a cross-sectional view taken along the lines 7-7;

FIG. 8 is a front right top perspective view thereof;

FIG. 9 is a front right bottom perspective view thereof;

FIG. 10 is a rear right top perspective view thereof; and,

FIG. 11 is a rear right bottom perspective view thereof.

1 Claim, 4 Drawing Sheets
